F. MOSER

WRENCH FOR SCREW TOP JARS

Filed April 7, 1926

Felix Moser INVENTOR

UNITED STATES PATENT OFFICE.

FELIX MOSER, OF HOLLAND, MICHIGAN.

WRENCH FOR SCREW-TOP JARS.

Application filed April 7, 1926. Serial No. 100,337.

The invention relates to a new form of wrench for screw-top jars, and it consists of a strap and a handle, as shown in the accompanying drawing. The object of the invention is to produce a wrench for screw-top jars that will open them with ease and close them tightly without injuring the cover.

Fig. 1 shows the wrench as applied to the jar cover in the act of closing it. It explains the direction of forces and the mechanical advantages.

Fig. 2 is a perspective view of the wrench loosely applied for opening the jar.

The wrench consists of a looped strap 1 of leather or similar material, both ends of which are fastened to the same edge 6 of a handle 2 by screws 3 or some other means.

The strap 1 is of such size that it will just fit the jar cover 4. The screws 3 are set back to increase the size of the loop so that it may be slipped on with ease. The handle 2 which may be about the thickness of the height of the jar cover and of convenient length and breadth, has a pointed or beveled end 5, this making one edge longer than the other. The strap 1 is attached to the longer edge 6, and on account of the pointed or beveled end of about 60° of the handle 1, is enabled to embrace about nine-tenths of the circumference of the cover 4, thus securing a maximum of friction and therefore taking a firm grip.

Mechanically the wrench has seven distinct movements or mechanical advantages as pointed out in Fig. 1. They are:

- A. The lever from the center of the cover to the end of the handle, a force which is common to all wrenches.
- B. A circular movement of the handle, pivoting on nearest screw 3.
- C. Strap following that movement tightening around the cover.
- D. The tightening of the strap around the cover in the opposite direction.
- E. The leverage exerted on the strap holding that end of the strap against the cover.
- F. The amount of friction (the grip established by the loop of the strap around the circumference of the cover).
- G. The leverage exerted tightening the

strap around the cover, which is not less than sixteen to one, after the force is applied and the point of the handle forces the strap parts to meet at g.

For closing the jar the wrench is applied as is shown in Fig. 1, force being applied as indicated by arrow a. This causes the handle to move slightly in the direction of arrow b, exerting a leverage of about four to one, the nearest screw 3 being the fulcrum. The same force will tighten the strap following arrow c, and also in the opposite direction following arrow d. The handle now pivoting on the center of the circle e exerts a leverage of sixteen to one against the cover, holding down that end of the strap. By this time the point of the handle will cause the strap to shorten its loop at g, tightening the strap around the cover with a leverage not less than sixteen to one.

Thus it can readily be seen that the grip on the cover on applying force as indicated by the arrows a becomes simultaneously absolutely locked; and as the point of the handle causes the strap to embrace nine-tenths of the circumference of the cover, a nonslip grip is established.

The cover can thus be tightly closed with comparative ease. For opening the operation is reversed as indicated in Fig. 2.

While the wrench as described and illustrated is intended to be a fruit-jar wrench, it is to be understood that such a wrench may be used for other purposes and various changes in shape may be made without departing from the spirit of the invention.

I claim:

A jar-top wrench including a handle having opposite sides of different lengths and beveled or tapered at one end at an angle of about sixty degrees adjacent the longer side, and having a loop or strap of flexible material secured at both its ends to the said longer side of the handle, the said tapered end being adapted to press into the bight of the loop and draw it closely around the jar top thus enabling the strap to grip about nine-tenths of the object to be turned.

FELIX MOSER.
